DESIGN FOR A MICROPHONE UNIT OR THE LIKE

Gabriel M. Giannini, New York, N. Y.

Application August 21, 1936, Serial No. 64,505

Term of patent 14 years

To all whom it many concern:

Be it known that I, Gabriel M. Giannini, a subject of the King of Italy, who has taken first papers for citizenship in the United States, residing at New York, county and State of New York, have invented a new, original, and ornamental Design for a Microphone Unit or the like, of which the following is a specification, reference being had to the accompanying drawing, which forms a part hereof.

Fig. 1 is a view in side elevation of a microphone unit or the like embodying the design.

Fig. 2 is a view in front elevation of the same unit.

The characteristic features of the design are shown in the drawing in solid black lines.

The design is intended especially for microphones, speakers, and microphone-speaker combinations.

I claim:

The ornamental design for a microphone unit or the like, substantially as shown and described.

GABRIEL M. GIANNINI.
